SAVINGS BANK

Original Filed Aug. 23, 1930

Inventor:
Albert C. Grunwald,
By appointment of the
Chittenden & Niles
Attest,

UNITED STATES PATENT OFFICE

ALBERT C. GRUNWALD, OF CHICAGO, ILLINOIS, ASSIGNOR TO THE AUTOMATIC RECORDING SAFE COMPANY, OF CHICAGO, ILLINOIS, A CORPORATION OF ILLINOIS

SAVINGS BANK

Original application filed August 23, 1930, Serial No. 477,431. Divided and this application filed March 21, 1932. Serial No. 600,259.

This invention relates particularly to a savings bank which simulates the form of a book.

The primary object is to provide a device 5 of this character with an improved slot-guard device.

The present application is a division of Grunwald application No. 477,431, filed August 23, 1930.

10 The invention is illustrated in a preferred embodiment in the accompanying drawing, in which—

Fig. 1 is a perspective view of a savings bank embodying the invention; Fig. 2, a plan 15 view of the same in open condition; Fig. 3, a broken perspective view of a perimetral member employed for simulating the gilded edges of the leaves of a book; Fig. 4, a section taken as indicated at line 4—4 of Fig. 2; Fig. 5, a broken section, on an enlarged scale, taken as indicated at line 5 of Fig. 2; Fig. 6, an enlarged broken sectional view taken as indicated at line 6 of Fig. 2; Fig. 7 a broken 20 perspective view showing the slot-guard device employed; Fig. 8, a perspective view of one of the pivoted slot-guards shown in Fig. 7; and Fig. 9, a broken perspective sectional view illustrating the manner in which the sliding locking member employed is mounted.

25 In the illustration given, A designates a box-like body forming the main portion of the casing; A', a closure constituting one sidewall of the casing; B, a locking device associated with the longitudinal edge-wall of the 30 main casing-section A; and C, a slot-guard device with which the casing-section A is equipped at one end.

The main casing-section A is shown as comprising a metal-plate 1, having an upturned 35 flange 1^a at one lateral edge, which constitutes the back of the safe; and a U-shaped peripheral member 2 which is in the form of an angle in cross-section. The member 2 comprises a longitudinal member 2^a and arms 2^b formed integrally therewith.

The member A' comprises a plate 3 which forms a sidewall of the casing, and a flanged U-shaped member 4, which is of suitable dimensions to be received within the member 2 40 when the bank is closed.

The members A and A' are connected at the free edge of the back 1^a by a piano-hinge 5. The casing is provided with a flexible covering 6, whose marginal portions are folded inwardly under the plates 1 and 3 and clampingly secured to the inner surfaces by means of the members 2 and 4. The horizontal flanges of the member 2 are provided with slots 7, through which extend clinching-lugs 8 which are struck inwardly from the plate 1. 55

Similarly, the horizontal flanges of the member 4 are provided with slots which receive clinching-lugs 9 which are struck inwardly from the plate 3, as shown in Fig. 6. Preferably, a padding-sheet 6^a, which may 60 be of paper, is pasted upon the inner surface of the cover-fabric 6 (before the cover is applied to the safe). The padding-sheet is of proper size to cover only the sides and back of the safe, and only the margins of the cover-fabric are folded about the edges of the metal. 70

The edge member 2 preferably is of brass which is given a satin finish, simulating the gilded edges of the leaves of a book.

The locking device B is shown as comprising 75 a housing member 10; a sliding-bolt 11, confined between the member 10 and the edge-wall afforded by the longitudinal member 2^a; a bolt-actuating spring 12; and a key-barrel 13, whose reduced outer end is received in a perforation 13^a of the member 2^a and whose reduced inner end is received in a perforated boss 14 with which the housing-plate 10 is provided.

The member 10 is of general Z-shaped 80 cross-section. Thus, the member comprises a strip 10^a, having an outturned short flange 10^b, which abuts against the free margin of the member 2^a, and having an inturned flange 10^c which rests upon the horizontal flange of the member 2^a and is secured by the clinching-lugs 8 which extend through the members. The member 10 is additionally secured in position by upturned lugs 15 with which the horizontal flange of the member 2^a 85 is provided at its free edge. Between the member 10 and the member 2^a is a space or longitudinal channel 16 in which the slide-bolt 11 operates. The member 11 is provided with inwardly-projecting lugs 11^a which 90

work in slots 10^d with which the vertical wall of the member 10 is provided. The member 11 is further provided with a lug 11^b which is adapted to be engaged by the blade of a key inserted in the barrel 13. Also, the member 11 is provided with an inturned lug 11^c which engages a small coil 17 which is housed in a longitudinal slot 18 with which the member 10 is provided. This slot is formed by severing the metal and striking it inwardly to form a longitudinal boss 18^a, as shown in Fig. 5.

The end portions of the housing member 10 are turned inwardly and cut on a bevel, thus providing brace-like ends 10^e.

The vertical wall of one of the arms 2^b is provided with a coin-slot 19.

The slot-guard device C is shown as comprising a bracket 20 and a pair of pivotally supported slot-guards 21. The bracket comprises an attaching flange 20^a which rests upon the horizontal wall 1 of the main casing-section, and upwardly bowed spring arms 20^b whose extremities are disposed adjacent the vertical wall of the arm 2^b. The bowed arms 20^b are shown separated by a slot 22. The extremities of the arms are provided with slots 20^c which are engaged by the pivoted members 21.

30 Each member 21 is shown as comprising an arm 21^a, and a supporting head 21^b. The head 21^b is somewhat angular in form, as appears from Fig. 6. The member 21, as a whole, is of general T-form. The arm 21^a projects across the coin-slot 19. When a coin is inserted through the slot, the arm is swung inwardly. In this action the head 21^b acts like a cam between the spring-arms 20^b and the horizontal flange of the member 2^b so that the extremities of the arms are sprung upwardly when a coin is inserted through the slot. The bowed arms 20^b rise a sufficient distance from the bottom wall 1 of the casing to form a stop for the member 21 when it is swung inwardly.

45 The purpose is to render it difficult for a coin to be abstracted after it has once been put in the savings bank.

The member 4 of the casing-section A' is provided with an inturned longitudinal flange 4^a, which has slots 4^b adapted to be engaged by the projections 11^a of the sliding locking bolt 11.

The improved slot-guard device is simple in construction and has been found to be reliable in practice.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

85 1. A savings bank comprising a casing having one wall provided with a coin-slot

and having another wall at right angles thereto; a bracket comprising a flange secured to said second-mentioned wall and a bowed spring-portion having a free extremity disposed adjacent to said first-mentioned wall; and a slot-guard having an angular head portion confined between the free end of the spring and said second-mentioned wall, and having a slot-guard portion extending through a recess in the extremity of said spring.

2. In combination: a book-form safe comprising a box-like main casing-section and a pivotally mounted closure forming one sidewall of the casing, one edgewall of said main casing-section being provided with a coin-slot; a resilient bracket having a flange secured to the sidewall of said main casing-section and having inwardly bowed spring-arms whose extremities abut against the edge-wall of the main casing-section below the coin-slot; and slot-guards having angular head portions confined between the end portions of the spring-arms and the sidewall of the main casing-section and having slot-guarding portions extending across said coin-slot.

ALBERT C. GRUNWALD.
